UNITED STATES PATENT OFFICE

171,882

AUXILIARY SUN VISOR AND ARTICLE HOLDER

Lawrence E. Carlsen, Huntington, Ind.

Application May 26, 1953, Serial No. 25,188

Term of patent 3½ years

(Cl. D14—6)

To all whom it may concern:

Be it known that I, Lawrence E. Carlson, a citizen of the United States of America, residing at Huntington, in the county of Huntington and State of Indiana, have invented a new, original, and ornamental Design for an Auxiliary Sun Visor and Article Holder, of which the following is a specification, reference being had to the accompanying drawing, forming a part thereof.

Figure 1 is a front elevational view of an auxiliary sun visor and article holder embodying my new design.

Figure 2 is a cross sectional view taken on line 2—2 of Figure 1.

Figure 3 is a side elevational view with the extended visor portion folded back.

Figure 4 is a fragmentary top plan view.

I claim:

The ornamental design for an auxiliary sun visor and article holder, as shown.
